UNITED STATES PATENT OFFICE.

SAMUEL WEBER, OF OSSINING, NEW YORK

FLYING-MACHINE.

1,005,381.

Specification of Letters Patent. Patented Oct. 10, 1911.

Application filed March 31, 1909. Serial No. 487,008.

To all whom it may concern;

Be it known that I, SAMUEL WEBER, a citizen of the United States, and residing at Ossining, in the county of Westchester and State of New York, have invented certain new and useful Improvements in Flying-Machines, of which the following is a specification, such as will enable those skilled in the art to which it appertains to make and use the same.

This invention relates to flying machines, and the object thereof is to provide a machine of this class which involves both the principle of the balloon and of the aeroplane, and which is provided with a suitable propelling apparatus and guiding and steering mechanism, and from which is suspended a suitable car or carriage above which and midway of the frame work of the machine is a bridge which ranges fore-and-aft and from which the propelling apparatus and steering or guiding mechanism are operated; a further object being to provide a flying machine which is simple in construction and convenient of manipulation, and with these and other objects in view the invention consists in a machine of the class specified constructed as hereinafter described and claimed.

The invention is fully disclosed in the following specification, of which the accompanying drawings form a part, in which the separate parts of my improvement are designated by suitable reference characters in each of the views, and in which:

Fig. 1 is a sectional side view of my improved flying machine, the section being on the line 1-1 of Fig. 3, Fig. 2 a front view thereof, Fig. 3 a sectional plan view, the section being on the line 3-3 of Fig. 2, Fig. 4 a diagrammatic view showing horizontally arranged aeroplanes used in one side of the machine and means for controlling the same, said aeroplanes and controlling devices being provided with counter parts at the opposite side of the machine, Fig. 5 a view similar to Fig. 4 but showing vertically arranged aeroplanes and devices for controlling the same, said aeroplanes and controlling devices being arranged centrally of the machine and ranging fore-and-aft, and Fig. 6 a view showing in transverse section a modified form of balloon construction which I may employ.

My improved flying machine comprises a main body or frame work, the transverse dimensions of which are much larger than the

fore-and-aft dimensions and which comprises top and bottom balloon members a and a^2 constructed and connected by a rigid frame work as hereinafter described. The balloon members a and a^2 are composed of metal casings a^3 , and these casings are of the same dimensions horizontally as the body or frame work of the machine, and said casings consist of top and bottom plates a^4 and a^5 which are brought together at the front and back sides and ends of said casings and secured together to form flanges a^6 which extend entirely around the said balloon members, and placed in said casings are inflatable bags a^7 . One inflatable bag a^7 may be used in each of the casings a^3 , or a number of bags of any desired dimensions may be placed in said casings which, it is designed, shall be of such capacity as when inflated to carry or support the weight of the machine.

The top and bottom balloon members a and a^2 are connected by a suitable frame work composed of rods b which are rigidly secured to the flanges a^6 of the balloon casings a^3 , and this connection may be made in any desired manner, and said rods may be arranged in any preferred form so as to give the required strength to the frame work and to support and hold in proper position the propelling apparatus and steering mechanism hereinafter described.

Placed centrally of and over the bottom balloon member a^2 and ranging fore-and-aft and rigidly secured to or in the frame work and forming in effect a part thereof, is a bridge c having a bottom c^2 of any suitable construction and centrally of which is placed a motor c^3 of any suitable construction, and the ends of the bridge c are provided with trunnions or other suitable supports c^4 from which is suspended a car or carriage c^5 which comprises a main part c^6 composed of any suitable open work and provided with end suspending devices c^7 .

The opposite side portions of the main frame or body work of the machine are provided with forwardly and backwardly directed open work supports d and d^2 , and the front supports d are provided with transversely arranged aeroplanes e and e^2 , and the rear supports d^2 with similarly supported aeroplanes e^3 and e^4 , and it will be observed that this construction is exactly the same at both sides of the machine and the position of the aeroplanes e and e^2 , and e^3 and e^4 is in a

plane midway between the top and bottom balloon members, and as clearly shown, the said supports d and d^2 project forwardly and backwardly of said balloon members.

5 The aeroplanes $e-e^2$ and e^3-e^4 are connected with shafts e^5 provided at their inner ends with sprocket wheels e^6 , and at the front of the machine and at each side of the bridge c are mounted horizontal shafts f which 10 range transversely of the machine and which are provided at their outer ends with sprocket wheels f^2 , and at their inner ends with sprocket wheels f^3 , and mounted on the sprocket wheels e^6 and f^2 are drive chains 15 or similar devices f^4 , this construction, as will be seen, being duplicated at the opposite sides of the machine.

At the rear end of the machine or opposite the shafts f are mounted similar shafts g 20 provided at their outer ends with sprocket gears g^2 and at their inner ends with sprocket gears g^3 , and drive chains g^4 similar to the drive chains f^4 are mounted on the sprocket wheels e^6 of the rear aeroplanes e^8 and e^9 and 25 on the sprocket gears g^2 of the shafts g , this construction being also duplicated at the opposite sides of the machine.

Mounted at the opposite sides of the bridge c and at the rear end thereof are 30 double sprocket gears h which are directly under the gears g^3 on the shafts g , and which are connected with said gears g^3 by drive chains h^2 , and at the opposite sides of the bridge c and at the front end thereof are 35 corresponding double sprocket gears i which are geared in connection with the gears f^3 of the shafts f by drive chains or similar devices i^2 , and the gears i are provided with hand wheels i^3 , and the gears h and i are 40 also connected by drive chains h^3 , and this construction, as will be seen, is duplicated on the opposite sides of the bridge, and by manipulating the hand wheels i^3 the aeroplanes $e-e^2$ and e^3-e^4 may be manipulated 45 as may be desired and as will be readily understood.

Mounted in the opposite side portions of the bridge c are sprocket gears j and in the outer side portions of the main frame or 50 body work of the machine are mounted aeroplanes j^2 which range fore-and-aft and are mounted on shafts provided at their front ends with sprocket gears j^3 , and the sprocket gears j are geared in connection with the 55 sprocket gears j^3 by drive chains j^4 , and the sprocket wheels j are provided with hand wheels j^5 and by means of the hand wheels j^5 and the gearing connected therewith and with the aeroplanes j^2 may be turned into 60 any desired position.

Connected with the front and rear parts of the main frame or body work of the machine and at the front and rear ends of the bridge c are forwardly and backwardly directed supports k , and in the forwardly di-

rected support k are mounted vertically arranged Rudders k^2 and k^3 , and in the backwardly directed support k are similar Rudders k^4 and k^5 , and these Rudders are connected with shafts, the lower ends of which 70 are provided with sprocket gears k^6 .

Mounted at the rear end of the bridge c and at the opposite sides thereof are gears or idlers m , and below said gears or idlers are other gears or idlers m^2 , and mounted 75 at the front of the bridge and at the opposite sides thereof are gears or idlers m^3 which correspond with the gears or idlers m and below which are gears or idlers m^4 which correspond with the gears or idlers m^2 , and mounted over the front end portion 80 of the bridge c is a hand wheel n provided with a drum n^2 , and wound on the drum n^2 is a drive chain or similar device o which passes around the gears or idlers m and m^2 85 and around the gears or idlers m^3 and m^4 and around the sprocket gears k^6 of the Rudders k^2 and k^5 and which contacts with the sprocket wheels k^6 of the Rudders k^3 and k^4 and by manipulating the hand wheel n the 90 said Rudders at the front and back of the machine may be thrown into any desired position.

Mounted at the opposite sides of the rear end portion of the bridge c and above said bridge are propeller shafts p , the rear end portions of which project rearwardly of the main frame or body work and are provided with propellers p^2 , and the front end portions of which are provided with propellers 100 p^3 , and the front ends of the propeller shafts p are provided with sprocket gears p^4 .

The motor c^3 is provided with a shaft r , and said shaft is provided with a double sprocket gear r^2 , and the double sprocket gear r^2 is geared in connection with the sprocket gears p^4 on the propeller shafts p by drive chains r^3 .

The propeller shafts p are provided with supports s which are arranged as shown in 110 the drawing so as to give said shafts the strongest possible support involving the least necessary weight, and this is also true of the supports of the aeroplanes $e-e^2$ and e^3-e^4 and of the supports of the Rudders $115 k^2-k^3$ and k^4-k^5 .

In the operation of this machine, the balloon members a and a^2 serve by reason of 120 their form and dimensions as stationary aeroplanes and aid in the movement of the machine, while the aeroplanes $e-e^2$ and e^3-e^4 may also be manipulated for the same purpose, and these aeroplanes also aid in guiding and steering the movement of the machine upwardly and downwardly, and the Rudders k^2-k^3 and k^4-k^5 in addition to serving as ordinary Rudders for steering or guiding the machine also, as will be understood, serve as aeroplanes when the direction of the machine is fixed or deter- 125

mined; and it will be understood that while with the construction shown, the aeroplanes $e-e^2$ and e^3-e^4 at the front and back of the machine are manipulated by the same means 5 and at the same time, other methods of operation may be employed. My invention is not limited to these arrangements, and this also applies to the means for operating or controlling the rudders k^2-k^3 and k^4-k^5 . It 10 will also be observed that the side aeroplanes j^2 in the construction shown are adapted to be manipulated separately, but the construction by which this is accomplished may also be changed, and said aeroplanes may be 15 otherwise operated if desired.

Although I have shown and described the balloon members a and a^2 as composed of outer casing in which are placed inflatable bags, I desire it understood that these casings may be made in any desired manner 20 and may be provided with suitable reinforcing or brace work and may be composed of separate parts if desired, and the inflatable bags therein may also be formed of 25 separate parts or members and may be of any preferred construction, and other changes in and modifications of the various other parts of my improved flying machine as herein shown and described, in connection 30 with those specifically pointed out above, may be made within the scope of the appended claims, without departing from the spirit of my invention or sacrificing its advantages; and I reserve the right to make 35 all such alterations and amendments therein as fairly come within the scope of the invention.

As hereinbefore stated, the balloon members of the main frame or body are intended 40 to carry or raise the machine, but by putting the propelling apparatus in operation, and by properly manipulating the forwardly and backwardly directed aeroplanes $e-e^2$ and e^3-e^4 , the said aeroplanes may 45 also be made to aid or assist in raising the machine as will be readily understood. It will also be understood that the party or parties in control of the machine will occupy the bridge c and other passengers and 50 supplies of any kind may be carried in the car or carriage c^6 , and the bridge c may also be made to carry articles or supplies of various kinds and classes.

Although I have described the top and bottom balloon members a and a^2 as composed of casings containing an inflatable bag or bags, said casings being flat or oblong in cross section so as to enable said balloon members to operate as aeroplanes, it is not 55 essential that single casings for this purpose be employed, and instead thereof I may employ the construction shown in Fig. 6 which represents a transverse section of one of these balloon members, said balloon member being composed of separate cylin-

drical casings a^8 which range forwardly and backwardly and each of which is provided with a separate internal inflatable bag a^9 , and in practice any desired number of these casings may be secured together 70 in any suitable manner so as to form the top and bottom balloon members a and a^2 and form a part of the main frame or body of the machine, and it will be understood that the top and bottom balloon members when made up in this manner will act 75 as aeroplanes, the same as in the construction of single casings and internal inflatable bags, as hereinbefore described.

Having fully described my invention, 80 what I claim as new and desire to secure by Letters Patent, is:—

1. In a flying machine, a main frame or body composed of top and bottom balloon members which are comparatively flat or 85 oblong in form in cross section and rigidly connected by an open frame work, said balloon members being composed of outer casings and inflatable bags placed therein, said main frame or body being provided at its 90 opposite sides with forwardly and backwardly directed supports in which are mounted aeroplanes, a central bridge construction placed in the main frame or body and ranging forwardly and backwardly, 95 propellers mounted on the opposite sides of said bridge work, other supports connected with the main frame or body and projecting forwardly and backwardly centrally thereof and at the opposite ends of said bridge work, 100 rudders mounted in said supports, means for operating said aeroplanes, devices for operating said propellers, and means for operating said rudders.

2. A flying machine composed of a main 105 frame or body comprising top and bottom balloon members rigidly connected by an open work frame construction, said balloon members being composed of outer casings and internal inflatable bags, a central forwardly and backwardly ranging bridge work, outwardly directed supports connected with the front and back portions of the main frame or body, transversely ranging aeroplanes mounted in said supports, 110 other forwardly and backwardly directed supports placed centrally of the main frame or body and between the first named supports, rudders mounted in said last named supports, forwardly and backwardly ranging 115 propeller shafts mounted at the opposite sides of the bridge work and provided at their front and rear ends with propellers, means for operating said aeroplanes, means for operating said propeller shafts, and 120 means for operating said rudders.

3. A flying machine composed of a main frame or body comprising top and bottom balloon members rigidly connected by an open work frame construction, said balloon 130

members being composed of outer casings and internal inflatable bags, a central forwardly and backwardly ranging bridge work, outwardly directed supports connected with the front and back portions of the main frame or body, transversely ranging aeroplanes, mounted in said supports, other forwardly and backwardly directed supports placed centrally of the main frame or body and between the first named supports, rudders mounted in said last named supports, forwardly and backwardly ranging propeller shafts mounted at the opposite sides of the bridge work and provided at their front and rear ends with propellers, means for operating said aeroplanes, means for operating said propeller shafts, and means for operating said rudders, said main frame or body being also provided at its opposite sides with pivotally supported aeroplanes, and means for operating the same.

4. A flying machine comprising a main body or frame work composed of top and bottom balloon members rigidly connected by an open work construction, said balloon members being approximately flat or oblong in cross section and being composed of outer casings and internal inflatable bags, aeroplanes mounted at the opposite side portions of said frame or body, forwardly and backwardly ranging propeller shafts mounted in the rear portion of the main frame work or construction and on the opposite sides of the central part thereof, propellers connected with the front and rear ends of said shafts, means for operating said shafts, and forwardly and backwardly directed rudders mounted centrally of the main frame work or body.

5. A flying machine composed of a main frame provided with top and bottom members forming main aeroplanes, a central forwardly and backwardly ranging bridge-work, outwardly directed supports connected with the front and back portions of

the main frame, transversely ranging supplemental aeroplanes movably mounted in said supports, other forwardly and backwardly directed supports placed centrally of the main frame and between the first named supports, rudders mounted in said last named supports, forwardly and backwardly ranging propelling shafts mounted at the opposite sides of the bridge-work and provided with propellers, means for operating said propeller shafts, and means for operating said rudders.

6. In an aeroplane, a main frame provided with top and bottom main aeroplane members, forwardly and backwardly directed supports at the opposite ends of the main frame and provided with horizontally supported and movable supplemental aeroplanes, other forwardly and backwardly directed supports midway of the main frame and provided with rudders, propelling devices, means for operating the supplemental aeroplanes, and means for operating said rudders.

7. In an aeroplane, a main frame provided with top and bottom main aeroplanes, other aeroplanes movably mounted in the end portions of the main frame transversely thereof, forwardly and backwardly directed supports connected with the opposite end portions of the main frame and provided with movable aeroplanes, other forwardly and backwardly directed supports arranged midway of the main frame and provided with rudders, and propelling devices also mounted transversely of the central portion of the main frame.

In testimony that I claim the foregoing as my invention I have signed my name in presence of the subscribing witnesses this 27th day of March 1909.

SAMUEL WEBER.
